UNITED STATES PATENT OFFICE.

JAMES ERNEST REID, OF MOORESTOWN, NEW JERSEY, AND CHARLES KIENLE, OF PHILADELPHIA, PENNSYLVANIA; SAID KIENLE ASSIGNOR TO SAID REID.

DENTAL INSTRUMENT.

1,335,987.

Specification of Letters Patent.

Patented Apr. 6, 1920.

Application filed May 27, 1919. Serial No. 300,188.

To all whom it may concern:

Be it known that we, JAMES E. REID, a citizen of the United States, residing at Moorestown, Burlington county, State of New Jersey, and CHARLES KIENLE, a citizen of the United States, residing at Philadelphia, in the county of Philadelphia and State of Pennsylvania, have jointly invented a certain new and useful Dental Instrument, 10 of which the following is a specification.

The principal objects of the present invention are, first, to provide a dental instrument in which the electric current that heats the tool proper can be conveniently and readily turned on and off manually, and is turned off automatically when the instrument is hung up; second, to simplify and improve the construction and operation of the instrument; third, to provide for the ready removal of the tool and its heater and for the replacement of the heater; fourth, to facilitate the making of repairs or renewals, and fifth, to provide for regulating the heat from the hand-piece of the instrument.

25 The invention will be claimed at the end hereof, but will be first described in connection with the embodiment of it selected from other embodiments for the sake of illustration in the accompanying drawings, 30 forming part hereof, and in which—

Figure 1, is a side view of an instrument embodying features of the invention.

Fig. 2, is a central sectional view, drawn to an enlarged scale, of the front or outer 35 end part of the instrument.

Fig. 3, is a view with the outer end of the hand-piece in section and with the interior parts in elevation, and

40 Fig. 4, is a similar view of the inner end part of the instrument shown in Fig. 3.

In the drawings, 1 is a tubular hand-piece slotted at 2, and provided at its rear end with an inlet 3 for the cable 4, carrying the leads 5 and 6. At the front end the hand-piece is provided with a thimble 7, for a purpose to be described. There is a frame arranged in the hand-piece and it consists of a conductor 8, provided with front and rear blocks 9 and 10 having confronting bridge contacts 11 and 12 of the spring finger variety. 13, is a traveler movable on the conductor 8, and provided with an insulated bridge piece 13^a, coöoperating with the contacts 11 and 12 to span them and 55 provide a path for current and to disconnect

them and interrupt the path for current. 14, is a finger piece, shown in the form of a ring, slidable on the hand-piece 1, and connected with the traveler 13 by a removable screw or pin 15, working in the slot 2. 60 16 and 17 are heater contacts, of the spring-finger variety, projecting from the front block 9. The contacts 17 are connected with the conductor 8 as by means of a cross-connection 18. 19, is a hollow tool shank provided internally with a heating coil 20, and detachably mounted in the thimble 7, with the heater terminals 21 and 22 in detachable engagement with the heater contacts 16 and 17. The path for current may be traced, 70 Fig. 2, from 5, to contacts 12, to bridge 13^a, to contacts 11 and 16, to 21, through heater 20, to terminal 22, contact 17, cross-piece 18, conductor 8 and lead 6.

The position of the bridge piece 13^a is 75 determined by the position of the finger-piece 14, when the latter is in the position shown in Fig. 2 the circuit is closed and the heater 20 is on; when the finger-piece 14 is in the position shown in Fig. 3, the circuit 80 is open and the heater is off. The depressions 23 and 24 serve in coöperation with the contacts 11, as detents to prevent accidental movement of the bridge-piece 13^a.

Current is easily turned on and off to 85 regulate the temperature of the heater 20, by simply moving the finger-piece 14, and this can be done without interfering with the manipulation of the instrument. Again when the instrument is hung up in the usual 90 fork A, Fig. 1, the tines of the latter engage the finger-piece 14 and the weight of the instrument or the slight downward pressure given to it causes it to drop and so move the bridge 13^a, into the position shown in Fig. 95 3, with the result that the path for the circuit is automatically broken. It is an advantage of the described instrument that the tool shank 19, heater 20, and terminals 21 and 22 can be removed or unscrewed from 100 the thimble 7, as a unitary structure, and then the heater can be readily replaced by unscrewing 21 from 19; again the interior mechanism can be readily inserted and withdraw from the tubular hand-piece in 105 assembled condition.

If desired a rheostat operable from the hand-piece may be provided in addition to the parts described. In such case, Figs. 3 and 4, the block 10^a, with which the con- 110

2

acts 12 are connected, is of conducting material and the conductor 8 is insulated from it. An extension 23, of the block 10^a, carries an insulated rheostat coil 24, one end 5 of which is connected with the lead 5. 25, is the movable contact element of the rheostat and it is provided with a button 26, afforded sliding movement in an opening 27, through the hand-piece. By sliding the button 26, more or less resistance is interposed 10 in the circuit so that the heat of the tool can be regulated, and this can be done conveniently by the operator.

We do not limit the invention in matters 15 of detail and arrangement, but we claim:

1. A dental instrument comprising the combination of a tubular slotted hand-piece having leads through its rear end, a frame arranged in the hand-piece and consisting 20 of a conductor provided with front and rear insulating blocks having confronting bridge-contacts, a traveler movable on the conductor and provided with an insulated bridge-piece coöperating with said contacts, 25 a finger-piece slidable on the hand-piece and connected with the traveler through the slot of the hand piece, heater contacts on the front block, and a tool shank provided with a heater and detachably mounted on 30 the front end of the hand piece and having the heater terminals in detachable engagement with the heater contacts, substantially as described.

2. A dental instrument comprising in 35 combination, a tubular hand-piece, a heater at one end thereof, spaced contacts mounted in the hand-piece and current connections therefor, a bridge movable endwise in and of the hand-piece to span and to disconnect 40 said contacts, and a slide movable endwise of and on the hand-piece and connected with the bridge, substantially as described.

3. In a dental instrument the combination 45 of a conductor, spaced blocks carried by the conductor and provided with confronting contacts, a traveler slidable on the conductor and provided with a bridge coöperating with the contacts, a hand-piece inclosing

said parts and provided with a slot, and a finger-piece slidable on the hand-piece and 50 connected through the slot with the traveler, substantially as described.

4. In a dental instrument the combination of a hand piece, a tool shank detachably connected with the hand piece, a heater 55 detachably mounted in the tool shank and detachable along with the shank from the hand piece, and detachable contacts between the heater and hand piece and respectively attached to the hand piece and heater, 60 substantially as described.

5. In a dental instrument the combination of a tubular hand-piece provided with a slot, a conductor provided with spaced blocks having confronting circuit contacts 65 and heater contacts, a traveler having a bridge and movable on the conductor between the confronting contacts, a ring on the hand-piece, and a detachable connection arranged in the slot and connecting the ring 70 and traveler, the conductor and traveler and blocks and their accessories being removable as a unitary structure.

6. In a dental instrument the combination of a tubular hand-piece, a detachable 75 tool provided with a heater, a finger-piece slidable on the hand-piece, and circuit connections including a switch operable by the hand-piece and contacts automatically disengageable from the heater, substantially 80 as described.

7. In a dental instrument the combination of a hollow hand-piece, and circuit control mechanism insertible and removable as a unit in respect to the hand-piece and 85 comprising a pair of blocks both provided with contacts and one provided with a rheostat coil and a conductor connecting said blocks and sliding elements accessible from the outside of the hand-piece and coöperat- 90 ing with the contacts to close and open circuit, and with the rheostat coil to regulate circuit, substantially as described.

JAMES ERNEST REID.
CHARLES KIENLE.
